US00D893740S

(12) **United States Design Patent** (10) **Patent No.:** **US D893,740 S**
(45) **Date of Patent:** **** Aug. 18, 2020**

(54) **UV STERILIZER**

(71) Applicant: **Shenzhen Easycare Intelligence Technology Co., Ltd**, Shenzhen (CN)

(72) Inventor: **Jianfeng Lv**, Shenzhen (CN)

(73) Assignee: **SHENZHEN EASYCARE INTELLIGENCE TECHNOLOGY CO., LTD**, Shenzhen (CN)

(**) Term: **15 Years**

(21) Appl. No.: **29/686,742**

(22) Filed: **Apr. 8, 2019**

(30) **Foreign Application Priority Data**

Jan. 14, 2019 (CN) 2019 3 0017735

(51) **LOC (12) Cl.** **24-01**

(52) **U.S. Cl.**

USPC **D24/217**

(58) **Field of Classification Search**

USPC D24/216, 217, 218, 219, 231, 232, 108, D24/164; D3/201, 203.1, 203.2, 203.3,

D3/203.4, 294; D32/1, 25

(57) **CLAIM**

The ornamental design for a UV sterilizer, as shown and described.

DESCRIPTION

FIG. 1 is a perspective view of a UV sterilizer showing my new design;

FIG. 2 is another perspective view of the UV sterilizer showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The broken lines depict portions of the UV sterilizer that form no part of the claim, the broken lines form no part of the claimed design.
